UNITED STATES PATENT OFFICE.

WILLIAM A. HAWTHORNE, OF CARSON, NEVADA.

WINDOW-SASH LOCK.

SPECIFICATION forming part of Letters Patent No. 628,267, dated July 4, 1899.

Application filed July 14, 1898. Serial No. 685,946. (No model.)

To all whom it may concern:

Be it known that I, WILLIAM A. HAWTHORNE, a citizen of the United States of America, residing at Carson, in the county of Ormsby and State of Nevada, have invented certain new and useful Improvements in Window-Sash Locks, of which the following is a specification, reference being had therein to the accompanying drawings.

10 My invention relates to certain new and useful improvements in window-sash locks.

My invention consists in the novel combination and arrangement of parts hereinafter more fully described, illustrated in the accompanying drawings, and particularly pointed out in the claim.

15 In the drawings, Figure 1 is a perspective view showing the elongated piece of spring metal in position. Fig. 2 is a cross-sectional view thereof, showing the locking means.

20 Fig. 3 is a perspective view of the elongated piece of spring metal. Fig. 4 is a disassembled view of the locking means.

25 Referring to the drawings, in which like numerals of reference indicate corresponding parts throughout the several views, 1 indicates the window-frame of the ordinary construction, having the usual vertical extensions 2, 3, and 4 suitably secured thereto, forming 30 between them the inclosing or sliding spaces 5 and 6 for the window-sash.

35 Secured in the spaces 5 and 6, at one side, as at 8, is an elongated piece of spring metal 9. This piece of metal is curved, as shown, and is adapted to operate against the inner edge of the sash. The inner edge of the sash is rabbeted, forming the space 10 and the rib or flange 11. The rabbeted portion of the sash is inclined, as shown at 12.

40 The sash 7 has a slot formed therein, this slot being of greater diameter at its inner edge, as at 13, than at its outer end, as at 14. Operating in the said slot is a locking-pin 15, having a suitable head 16. This locking-pin 45 is actuated by the coil-spring 17, which surrounds the same and is arranged within the enlarged portion of the slot between the pin 18, extending transversely through the pin

15, and the inner end of said enlarged portion of the slot.

50

The metal strip has apertures 19 formed therein a suitable distance apart for the operation therein of the end of the locking-pin.

20 are apertures formed in the metal strip for the purpose of securing the same to the sash by means of the screws 21.

The spring-metal strip while serving to form a part of the lock also incidentally acts as a weather-strip and permits the dispensing with of the ordinary weather-strip or parting-bead.

60 It is thought that no further explanation is necessary, owing to the simplicity of my device.

65 It will be noted that various changes may be made in the details of construction without departing from the general spirit of my invention.

Having thus fully described my invention, what I claim, and desire to secure by Letters Patent, is—

70 A window-sash lock consisting of a spring-metal strip having its one edge curved outwardly and its other edge secured within the recess of the window-frame, said strip being 75 provided throughout its secured edge with a series of apertures, combined with a window-sash rail having a rabbet to receive the projecting edge of said spring-strip, said sash-rail being further provided with a recess and 80 an opening registering therewith, a locking-pin arranged in said recess and operating through said opening and adapted to engage in the apertures of the spring-metal strip to lock the sash, a stop-pin secured in said locking-pin, and a coil-spring arranged upon said locking-pin between the stop-pin and the inner end of the recess in the sash-rail for holding said locking-pin in locking engagement with the metal strip, substantially as set forth. 85 90

In testimony whereof I affix my signature in the presence of two witnesses.

WILLIAM A. HAWTHORNE.
